UNITED STATES PATENT OFFICE

RICHARD RUEMELIN, OF ST. PAUL, MINNESOTA

ADJUSTABLE PORTABLE FOLDING SAND-BLAST CABINET

Application filed January 17, 1929. Serial No. 333,233.

My invention relates to a portable and folding sand blast cabinet designed to permit the sand blasting of monuments and stones so that the operator can easily set up the cabinet wherever the stone is located, and by means of the blasting apparatus any suitable design may be sand blasted on the stone with a minimum loss of blasting sand and confining the dust of the sand blasting operation within the cabinet so that the operator may more easily accomplish the task of sand blasting the stone.

A feature of my invention resides in a sand blast cabinet which is provided with an adjustable opening adapted to fit up in close relation to the surface of the stone to be cut. The adjustable nature of the opening is such that it can be adjusted to inclined or straight surfaces of the stone and thus permit the cabinet to be readily used to provide an enclosure for sand blasting monuments in the cemeteries of various shapes and designs.

It is also a feature of my invention to provide a sand blast cabinet adjustable in height and having a sight screen for the operator, together with a slotted aproned opening through which the sand blast nozzle is adapted to be projected in a manner so that it can be freely operated in the desired direction.

My invention includes means for collecting the spent sand at the lower portion of the sand blast cabinet.

The feature of my invention which includes the collapsing of the cabinet into a small compact state is very desirable permitting it to be carried in a convenient manner and thereby providing a portable folding cabinet which is quickly adjustable into operative position or may be stored away in a small compact state.

These features together with other objects and details of the invention will be more fully and clearly set forth in the specification and claims.

In the drawings forming part of this specification:

50 Figure 1 is a perspective view illustrating

my portable folding sand blast cabinet as it would appear in use.

Figure 2 illustrates a side view of the same, showing the cabinet adaptable to different shaped stones.

Figure 3 is a perspective view of my cabinet folded up into a compact state for carrying.

Figure 4 is a sectional detail through the front and slotted apron.

In the drawings my sand blast cabinet A is designed with supporting standards 10 having bracket supports 11 which are adjustably held to the standards 10 by the set screws 12.

The portable folding sand blast cabinet A is formed with a body portion B of canvas or other suitable flexible material to form a flexible hood-like body having a top or roof 14, sides 15, a front 16 and a back portion 17. The sides, front and back converge together into a flexible funnel-like portion C so as to be directed into a receptacle 18 for collecting the spent sand in operation.

The top 14 is held adjustable to the standards 10 by the bracket members 19 having a set screw 20. The brackets 19 are adapted to support the side arms or bars 21 extending along the upper edge of the sides 15. A front bar 22 extends between the brackets 19 forming a rigid upper edge for the front 16. The bars 21 extend virtually parallel and are adapted to support the transverse rod 23 at their free end to which is pivotally connected the depending side bars 24. The bars 24 are held adjustable as illustrated in dotted outline in Figures 1 and 2, so that they can be adjusted to conform with the surface of the stone such as E or F, illustrated in the drawings. The lower free edge 25 of the bars 24 is adapted to support a transverse rod 26 which supports the upper edge of the back 17 of the flexible body B which forms the hood of the cabinet A. Thus the transverse rods 23 and 26 extend from one side to the other and provide the upper and lower edges of the opening 27, illustrated in dotted outline in Figure 1, in the cabinet A, which is placed up against the surface 28 of the stone E when it is desired to blast the surface of the stone. The opening 27 can

be adjusted as illustrated in Figures 1 and 2 to be placed against the surface of the stone, such as 28 or 29, of the stone F in Figure 2, so that the cabinet B will provide a closure about the surface to be blasted in a manner to collect the spent blasting sand and also the material which is blasted off of the stone either E or F and carry it into the receptacle 18 through the funnel-like portion C of the cabinet A. The funnel C is flexible and may be adjusted into the receptacle 18. I provide a work front 30 which is made of sheet metal or any other suitable material to provide a more or less rigid working front portion for my cabinet A. The front 30 is provided with a sight screen opening 31 which forms the necessary opening through which the operator can view the surface of the stone which is being blasted. Below the screened sight opening 31 I form a suitable opening 32 which is covered by the slited apron 33 formed of the three overlapping layers 33^a, 33^b and 33^c, which cover the opening 32 in a manner to form slits through which the blasting 25 nozzle and hose may extend, the lower edge of the slitted apron hanging free, and a multiplicity of overlapping strips of varying lengths and staggered being formed by the slitted apron 33 so as to thoroughly cover the opening 32 and protect the operator in operating the sand blast. The slitted apron 33 also permits the nozzle of the sand blast to be operated back and forth in the opening 32 and the strips of the slitted apron tend to automatically close the opening in the apron as the nozzle is moved from side to side. The members of the apron are sufficiently flexible to permit free operation of the nozzle.

40 My portable folding sand blast cabinet provides a suitable hood which is adjustable to the height of the stone to be sand blasted and which owing to its portable nature may be easily operated in cemeteries or other places where the stone may be positioned, eliminating the dust cloud and providing a clear vision to the operator and accessibility together with quick adjustment and having an opening which is adjustable to various 45 shapes of stones, together with the collecting of the spent sand in a suitable manner. All of these features are very desirable. The cabinet A may be quickly erected and adjusted, or it may be folded into a compact state, making it easy to carry. There is little or no waste in the blasting sand, thus providing a saving which is of importance in the continued use of my portable folding sand blast cabinet.

60 In accordance with the patent statutes I have described the principles of operation of my portable folding sand blast cabinet and while I have endeavored to illustrate the best embodiment thereof, I desire to have it understood that obvious changes may be made

within the scope of the following claims without departing from the spirit of my invention.

I claim:

1. A portable folding sand blast cabinet including, a flexible hood, said hood having a blasting opening, means to adjust said opening to the face of the stone to be blasted, one wall of said hood having a substantially rigid front portion including a sight screen and a multiple stepped slitted apron work opening, and a collector funnel-like portion adapted to direct spent sand into a receptacle. 70

2. A portable folding sand blast cabinet including, a flexible hood, means including a plurality of rod members for adjustably supporting said hood to the surface of a stone to be sand blasted, and means for collecting the spent sand by said hood for reclamation. 80

3. A sand blast cabinet including, a flexible body portion, one wall of said body portion having a rigid front portion, standards for adjustably supporting said body portion at various heights, said body portion having a blasting opening in one side thereof, means to adjust said opening to the face of the stone to be blasted, a sight screen, and a slitted apron covered opening formed in the front of said cabinet. 85

4. A sand blast cabinet including, a flexible body portion, one wall of said body portion having a rigid front portion including a sight screen and a slitted aproned opening for receiving the blasting nozzle, means for adjustably supporting said cabinet in front of a stone to be blasted, said body portion having a blasting opening, and means for adjusting said opening to the surface of a stone to be blasted, said body portion including a funnel-like collector portion adapted to direct spent sand into a receptacle. 95

5. A portable folding sand blast cabinet including, a body portion formed with top, sides, and a funnel-like bottom portion of flexible material, a sheet metal front having a sight screened opening, and an aproned work opening for the sand blasting nozzle, and means for adjustably supporting said cabinet adjacent a stone to be blasted, said cabinet being foldable into a compact state 100 when out of operation. 110

6. A portable folding sand blast cabinet for monument stones and the like including, a flexible hood-like body portion having a nozzle opening, a sight opening, an adjustable blasting opening, and a collector bottom portion adapted to collect the spent sand into a receptacle, standard means for supporting the same, said body and supporting means being foldable into a compact state to provide 115 a portable cabinet. 120

7. An adjustable folding sand blast cabinet comprising, a flexible body portion adapted to form a hood-like inclosure and having a sand blasting opening adapted to fit 130

against the article to be sand blasted, a screened sight opening, an aproned work opening, and a funnel-like lower portion adapted to direct spent sand to a receptacle, and means for adjustably supporting said cabinet in operating position.

8. A sand blast cabinet including, a hood, a substantially rigid front wall portion in said hood having an opening for a sand blast nozzle, and a closure apron extending over said nozzle opening formed by a series of overlapping slotted flexible members, some of said members being longer than others.

RICHARD RUEMELIN.
